MULTIPLE WINDOW PICTURE FRAME
OR THE LIKE

Charles Sadek, Bronx, N.Y.
(924 Broadway, New York, N.Y.)

Filed May 7, 1959, Ser. No. 55,809

Term of patent 3½ years

(Cl. D29—20)

FIG. 1

FIG. 1 is a top perspective view of a multiple window picture frame or the like showing my new design.

FIG. 2 is a front elevational view thereof, the rear, the sides, the top, and the bottom being substantially the same.

I claim:

The ornamental design for a multiple window picture frame or the like, substantially as shown and described.
